United States Patent Office

Des. 191,813
Patented Nov. 21, 1961

191,813

BARBECUE GRILL

Willard J. Murphy, 605 Harvey St., Ely, Minn., and David L. Painter, 718 Raleigh Road, Glenview, Ill.

Filed Feb. 20, 1961, Ser. No. 63,992

Term of patent 14 years

(Cl. D81—10)

The figure is a perspective view of a barbecue grill showing our design.

The appearance of the circular barbecue grill is the same on all sides.

We claim:

The ornamental design for a barbecue grill, substantially as shown and described.
